United States Patent Office

Des. 178,864
Patented Oct. 2, 1956

178,864

LAVABO PLANTER

Alfred A. Campana, Pennsauken, N. J.

Application May 10, 1956, Serial No. 41,428

Term of patent 7 years

(Cl. D35—3)

Fig. 1

Fig. 2

Fig. 1 is a front elevational view of a lavabo planter showing my new design; and

Fig. 2 is a side elevational view of the same.

I claim:

An ornamental design for a lavabo planter, as shown.
